UNITED STATES PATENT OFFICE.

ROBERT H. LANGFORD, OF SPRINGFIELD, TENNESSEE.

SHIPPING DEVICE.

1,421,964.

Specification of Letters Patent. Patented July 4, 1922.

Application filed January 12, 1921. Serial No. 436,704.

To all whom it may concern:

Be it known that I, ROBERT H. LANGFORD, a citizen of the United States, residing at Springfield, in the county of Robertson and 5 State of Tennessee, have invented certain new and useful Improvements in Shipping Devices, of which the following is a specification.

My invention relates to improvements in 10 shipping devices which, while capable of use for many purposes, is particularly constructed for shipping packages containing rolls of film employed in moving picture projectors or machines.

One object of my invention is the provision 15 of a shipping device which will positively protect the film containers and which will insure the package reaching its destination, as well as its safe return from the place of 20 shipment.

Another object of my invention is the provision of a shipping device which will permit of the instant insertion of the card bearing the address to which the package is destined and also the instant change to the 25 card-bearing the return address, such device protecting the address card to prevent tampering with the card or with the contents of the container.

Another object of my invention is the provision of a shipping device which will prevent access to the contents of the container and at the same time protect the address bearing element and which improvements 35 will be of such simple, inexpensive and practical construction as to make the device highly desirable and efficient in every particular.

With the attainment of the objects stated 40 in view, the invention consists of a container having a cover capable of being locked and means mounted in the cover and protected when said cover is locked to prevent access either to the said means which carry the 45 forwarding and return address element.

The invention further consists of a shipping device embodying novel features of construction and combination of parts substantially as shown, described and particularly defined by the claims, it being understood that any changes may be made in the construction which come within the scope 50 of the claims.

In order that the detail construction and 55 the operation of my invention may be fully understood and its many points of advantage

and features of merit be appreciated, I have shown in the accompanying drawing a structure embodying my invention, and in said drawing:

Figure 1 represents a perspective view of 60 a film carrying container equipped with my address or shipping device.

Fig. 2 represents a sectional view on the line 2—2 of Fig. 3, the view being on an 65 enlarged scale.

Fig. 3 represents a bottom plan view of the address carrying receiver or case, and

Fig. 4 represents a top plan view of the address card carrying element.

Referring by numeral to the drawings, in which similar numerals of reference denote like parts in all the views:

The numeral 1 designates the carrier or container adapted to receive the packages 75 containing the rolls of film, which container is provided with a cover 2 having a latch 3 secured by a suitable lock upon the hasp 4, the cover being provided with an opening 5 surrounded by a plate 6 acting as a retainer for the window or transparent covering 7.

Below the said window 7 and sight opening 6, is secured the box or casing 8 having struck up therefrom the clip or keeper 9, 85 which serves to retain the spring 10 having at one end the latch or engaging portion 11, said engaging or latch portion 11 serving to hold the slide 12, which fits in the casing 8, said slide having a finger loop 13 for the 90 purpose of inserting and withdrawing the slide. The slide is formed in its upper face with a pocket or recess 14, forming a receptacle for the address cards 15, such cards bearing upon one face the address to which 95 the container is shipped and upon its other face the return address or the address to which the container is to be returned.

The slide may have the pocket or recess of any desired depth to accommodate any 100 number of cards bearing addresses, and to retain the cards in place a spring clip 16 is employed, which bears upon one end of the cards and retains them in proper place.

The manner of using my invention is so 105 obviously apparent from the description and drawings, that it seems unnecessary to elaborate upon the matter, but it must be at once apparent that the device insures the forwarding and return of the container; that 110 the locking of the container protects its contents as well as the address-carrying ele-

ment; and that the improvement adds practically nothing to the cost of the container, while greatly increasing its efficiency, desirability and practicability.

5 I claim:

1. A shipping device of the character described, consisting of a container, a cover for said container having a sight opening and locking means, a window protecting said sight opening, a plate on the upper part of the cover surrounding said opening and retaining the window in place, a casing secured below said window, a slide mounted in said casing and having a pocket to carry address cards, and means in the casing for securing the slide in place, consisting of a catch mounted in the casing and engaging the said address carrying element.

10 said sight opening, a plate on the upper part of the cover surrounding said opening and retaining the window in place, a casing secured below said window, a slide mounted in said casing and having a pocket to carry

15 address cards, and means in the casing for securing the slide in place.

2. A shipping device of the character described, consisting of a container, a cover for said container having a sight opening and locking means, a window protecting said sight opening, a plate on the upper part of the cover surrounding said opening and retaining the window in place, a casing secured below said window, a slide mounted in said casing and having a pocket to carry address cards, and means in the casing for securing the slide in place, consisting of a catch mounted in the casing and engaging the said address carrying element.

20 In testimony whereof I affix my signature. 30

ROBERT H. LANGFORD.
